WILLIAM S. HADAWAY, JR., OF NEW ROCHELLE, NEW YORK.

HEAT-REGULATING SYSTEM.

1,155,482.

Specification of Letters Patent.

Patented Oct. 5, 1915.

Application filed April 17, 1914. Serial No. 832,410.

To all whom it may concern:

Be it known that I, WILLIAM S. HADAWAY, Jr., a citizen of the United States of America, and a resident of New Rochelle, Westchester county, and State of New York, have invented certain new and useful Improvements in Heat-Regulating Systems, of which the following is a specification, reference being had to the accompanying drawings, 10 forming a part thereof.

My invention relates to heat regulators and particularly to systems of regulation for electrically heated crucibles or melting pots for type-setting machines.

15 One object of my invention is to provide a simple and reliable system of the aforesaid character that shall be adapted for automatically regulating the heat generated in accordance with the temperature of the 20 molten metal in the body of the melting pot.

Another object is to embody in such a system, means for heating the mouth and throat of a crucible as well as imparting heat to the metal in the well of a crucible, 25 and means for adjusting the electrical input of the well or immersion heaters relative to that of the mouth and throat heaters in order to render the device readily adaptable to widely different classes of work.

30 Another object is to provide a receptacle having a body, adapted to contain a large mass of molten material having a large heat capacity, and an outlet or branch adapted to receive periodically or contain a small mass 35 of molten material having a relatively small heat capacity, and a heater for the outlet or branch adapted to maintain the small mass at the temperature of the large mass.

Other objects and advantages of my invention will be set forth hereinafter, and in order that my invention may be thoroughly understood I will now proceed to describe the same in the following specification, and then point out the novel features thereof in 45 appended claims.

Referring to the drawings: Figure 1 is a diagrammatic view of a heat regulating system embodying my invention, a crucible and its heaters being indicated in outline. Figs. 50 2 and 3 are simple diagrams illustrating the circuit connections established between the various heaters with which the crucible is equipped.

10 is a crucible or melting pot for a linotype or other type-setting machine. Within

the body of the heater where they are adapted to be immersed in molten metal, are a pair of heaters 11, composed of a main section 11^a and a relatively low resistance section 11^b, and 12, which are preferably curved 60 to surround the well 13 of the crucible, and a thermometer tube 14. The neck or outlet 15 of the crucible is provided with a mouth heater 16 and a throat heater 17. The structure and specific mechanical arrangement of these heaters form no part of my present invention and may, for example, be such as is shown in my copending application Serial No. 827,361 filed March 26, 1914. 65

The thermometer bulb 14 is connected by 70 a tube 18 to a regulator 19 which comprises a pair of stationary contacts 20 and 21 and a movable contact 22 which is adapted to make contact with one or the other of the stationary contacts whenever the temperature of the metal in the body of the crucible varies beyond predetermined limits in either direction. This regulator *per se*, forms no part of my present invention and may, for example, be constructed like that 75 set forth and described in my copending application Serial No. 827,362 filed March 26, 1914.

23 is a switch which may be opened or closed according to the work being done on 80 the type-setting machine as hereinafter more fully explained.

The heaters may be supplied with energy from any suitable source (not shown) 85 through line conductors 25 and 26.

27 and 28 are fuses located in the line circuit and 30 is a manually operated line switch. The circuits are governed not only by the switches 23 and 30 but also by an electrically operated switch 31 which comprises 90 a pivoted arm 32 carrying movable contacts 33 and 34, a solenoid coil 35, and a core 36 operatively connected to the arm 32, and arranged to move the contacts 33 and 34 95 into engagement with stationary contacts 37 and 38 when the coil 35 is energized. A bridging contact 39 is also operatively connected to the core 36 and is adapted to bridge a pair of stationary contacts 40 when the coil is energized. Another auxiliary switch 41 is connected to the arm 32 by a link 42 and is closed to short circuit a portion of a resistance 43 when the solenoid coil 35 is deenergized. 100

105 The circuit connections for the system will 110

now be traced in connection with the description of its operation which is as follows: It may be assumed that the line switch 30 is open, the solenoid coil 35 deenergized, the auxiliary switch 41 closed and the contacts 33, 34 and 39 separated respectively from the contacts 37, 38 and 40. Assuming further that the metal in the crucible is cold and that the contact 22 of the regulator is in engagement with the stationary contact 20; if now the line switch 30 is closed energy is supplied from the line conductor 25 through fuse 27, one blade of line switch 30, a conductor 50, contacts 20 and 22 of the regulator, conductor 51, coil 35 of the solenoid, conductor 52, switch 41 which is closed, a portion of the resistance 43, conductor 53, opposite blade of line switch 30, and fuse 28 to opposite line conductor 26. The coil 35 when energized actuates the core 36, opens the switch 41, thereby introducing additional resistance in the circuit of the solenoid, and moves the contacts 33, 34 and 39 into engagement with the stationary contacts 37, 38 and 40. The circuit connections now established through the heaters depend upon the switch 23 which is intended to be open when the type-setting machine is operating on newspaper work or the like, where small and light slugs are produced. Assuming that the switch 23 is closed, a circuit is established from conductor 50 through the arm 32 of the solenoid switch 31, contacts 33 and 37, a conductor 54, coil 35 of the solenoid and conductor 52 from which point, circuit is completed as before. A holding circuit is thus established for the solenoid, which is independent of the regulator contacts 20 and 22. The solenoid switch therefore remains closed until the regulator contact 22 is moved in the opposite direction into engagement with contact 21 as herein-after explained. Another circuit is established from the arm 32 through contacts 34 and 38, a conductor 55 through the resistances 11^a (11^b being short circuited when switch 23 is closed) and 12, which are connected in multiple relation, and conductor 56 which is connected through conductor 53, to the line conductor 26. Another circuit is established for conductor 50, through conductor 57, throat heater 17, conductor 58, mouth heater 16, conductor 59, conductor 60, switch 23, conductor 61, and solenoid contacts 39 and 40, circuit being completed through conductor 53 as before.

The circuit connections shown in Fig. 2 now obtain. If it is now assumed that the temperature of the metal in the body of the crucible is sufficiently raised so that movable contact 22 of the regulator engages stationary contact 21, solenoid coil 35 is short circuited, and the contacts 33-34-39 are separated from the stationary contacts 37-39 and 40. The switch 41 is at the same

time closed. Under these conditions the circuit traced through the immersion heaters 11^a and 12 is interrupted and the circuit traced through the throat and mouth heaters 16 and 17 is now completed from conductor 59 through conductor 62, the low resistance section 11^b of the heater 11, conductor 56 and conductor 53 to the opposite side of the line. This circuit is independent of the solenoid switch and it is evident from the foregoing that when the temperature of the crucible is below a predetermined value, the two immersion heaters 11^a and 12 are connected across the circuit in multiple relation as shown diagrammatically in Fig. 2, 80 while the throat and mouth heaters are connected in series relation across the circuit so long as the switch 23 is closed.

When the temperature in the crucible attains a predetermined value, the contacts 21 85 and 22 move into engagement and the immersion heaters 11^a and 12 are cut out of circuit, the relatively low resistance section 11^b of the immersion heater 11 being connected in series with the mouth and throat 90 heaters as shown in Fig. 3. Thus, the amount of energy supplied to the mouth and throat heaters is reduced and the energy is practically cut off from the immersion heaters. 95

The conditions above assumed, cause the system to operate advantageously for light work such as type-setting for newspapers, since the amount of heat generated in the mouth and throat heaters is large, except 100 when the temperature of the metal in the body of the crucible exceeds a predetermined amount. If this relation is maintained for making relatively heavy slugs such as is used for books, the slugs would 105 not be properly cast because the opening of the crucible would be kept at too high a temperature by reason of the mass of hot metal which is carried over at each stroke. Under these conditions therefore, the switch 23 is left open and the relatively low resistance section 11^b of the immersion heater 11 is permanently connected in series with the mouth and throat heaters 16 and 17 irrespective of the regulator 19. Under those 110 conditions the regulator serves merely to introduce and exclude the immersion heaters 11^a and 12 from circuit. Fig. 3 represents correctly the arrangement of connections 115 for heavy as well as light work when the regulator contact 22 engages stationary contact 21 the short circuit for the resistance section being interrupted at the contacts 39 and 40 irrespective of the position of the switch 23. The arrangement of circuits for heavy work, when the regulator occupies an intermediate position or engages the stationary contact 20, corresponds to that shown in Fig. 2 except that the switch 23 is 120 open instead of closed. 130

The advantages of my regulating system will be readily apparent to those familiar with this art and among others the following may be mentioned. First, the same apparatus is adaptable for use on widely different classes of work; second, the regulation depends on a definite and controlling temperature, viz., that of the metal in the body of the crucible; third, two immersion heaters are provided either of which is sufficient to melt the type metal in the crucible and consequently the apparatus is unlikely to become sufficiently damaged, as for instance, by the failure of both of the heaters to make it impossible to remove the immersion heaters for repairs without applying heat from some external source. In other words, two parallel connected units are provided to avoid the possibility of their being permanently set in cold metal.

It is evident that the circuit connections of the system may be modified within the spirit and scope of my invention and that other variations may be effected, and I intend that only such limitations be imposed as are indicated in the appended claims.

What I claim is:

1. A heat regulating system comprising an immersion heater, an outlet heater, and means for connecting a section of the immersion heater in series with the outlet heater to relatively reduce the heat generated in the outlet heater.

2. A heat regulating system for type-setting machine crucibles comprising an immersion heater, an outlet heater, and means dependent upon the temperature in the crucible for connecting a section of the immersion heater in series with the outlet heater and disconnecting the remainder of the immersion heater from the circuit.

3. A heat regulating system for type-setting machine crucibles comprising an outlet heater, a heater for the body of the crucible having a section connected in series with the outlet heater and means dependent upon the temperature in the crucible for disconnecting the remainder of the body heater from the circuit.

4. A heat regulating system for type-setting machine crucibles comprising an immersion heater, an outlet heater, a solenoid switch for connecting and disconnecting the immersion heater to and from the circuit, dependent upon the temperature in the crucible, and means for either connecting the outlet heater to the supply circuit or connecting it thereto with a portion of the immersion heater.

5. A heat regulating system for type-setting machine crucibles comprising an immersion heater, an outlet heater, automatic means for energizing and deenergizing the immersion heater, and means for varying the heat generated in the outlet heater.

6. A heat regulating system for type-setting machine crucibles comprising an immersion heater, an outlet heater, automatic means for energizing and deenergizing the immersion heater in response to variations in the temperature of the metal within the crucible, and means for varying the heat generated in the outlet heater.

7. A heat regulating system for type-setting machine crucibles comprising an immersion heater, an outlet heater, and automatic means dependent upon predetermined variations of the temperature of the metal within the crucible for opening and closing the circuit of the immersion heater and varying the heat generated in the outlet heater.

8. A heat regulating system for type-setting machine crucibles comprising a pair of body heaters connected in multiple relation, mouth and throat heaters in series relation, and means for connecting one terminal of the series to an intermediate point in one of the body heaters.

9. A heat regulating system for type-setting machine crucibles comprising a pair of immersion heaters connected in multiple relation, outlet heaters connected in series relation, and means for closing and interrupting the multiple circuit and for connecting a portion of one of the immersion heaters in the series whenever the multiple circuit is disconnected.

10. A heat regulating system for type-setting machine crucibles comprising a pair of immersion heaters connected in multiple relation, one of said heaters comprising a relatively low resistance section, mouth and throat heaters in series relation and connected in series with said low resistance section of the immersion heater, and means for short circuiting said low resistance section of the immersion heater.

11. In combination, a receptacle adapted to contain a relatively large mass of hot liquid and a branch adapted to receive hot liquid from the receptacle, an auxiliary heater for the branch and means dependent upon the temperature of the relatively large mass in the receptacle for regulating the heat generated in the auxiliary heater.

12. In combination, a receptacle adapted to contain a relatively large mass of hot liquid and a branch adapted to receive hot liquid from the receptacle, an auxiliary heater for maintaining the liquid in the branch at the temperature of the relatively large mass in the receptacle, and means for varying the energy translated by said auxiliary heater.

13. In combination, a receptacle adapted to contain a relatively large mass of hot liquid and a branch adapted to receive hot liquid from the receptacle, an auxiliary heater for maintaining the liquid in the branch at the temperature of the relatively large mass in the receptacle.

- large mass in the receptacle, and means for automatically varying the energy translated by said heater, dependent upon the temperature of the liquid in the receptacle.
- 5 14. In combination, a crucible adapted to contain a relatively large mass of molten metal, an outlet from which said molten metal is adapted to be periodically discharged, and an auxiliary electric heater for 10 maintaining the molten metal in the outlet at the temperature of the relatively large mass in the crucible.
15. In combination, a crucible adapted to contain a relatively large mass of molten metal, an outlet from which said molten metal is adapted to be periodically discharged, an auxiliary electric heater for maintaining the molten metal in the outlet at the temperature of the relatively large 15 mass in the crucible, and means for varying the electrical input of said auxiliary electric heater.
- 20 16. In combination, a crucible adapted to contain a relatively large mass of molten metal, an outlet from which said molten metal is adapted to be periodically discharged, an auxiliary electric heater for maintaining the molten metal in the outlet at the temperature of the relatively large 25 mass in the crucible, and means for automatically varying the energy translated by said heater, dependent upon the temperature of the molten metal in the crucible.
- 30 17. In combination, a crucible adapted to contain a relatively large mass of molten metal, an electric heater for the crucible, an outlet adapted to receive molten metal periodically from the crucible, and an auxiliary electric heater for maintaining the molten metal in the outlet at the temperature of the relatively large mass in the 35 crucible.
- 40 18. In combination, a crucible adapted to contain a relatively large mass of molten metal, an electric heater for the crucible, an outlet adapted to receive molten metal periodically from the crucible, an auxiliary electric heater for maintaining the molten metal in the outlet at the temperature of the relatively large mass in the crucible, and means dependent upon the temperature of the relatively large mass in the crucible for regulating the energy translated by said auxiliary heater.
- 45 55 19. In combination, a crucible adapted to contain a relatively large mass of molten metal, an electric heater in the crucible, an outlet adapted to receive molten metal periodically from the crucible, an auxiliary electric heater for maintaining the molten metal in the outlet at the temperature of the relatively large mass in the crucible, and a regulator comprising a thermometer tube immersed in the relatively large mass of 60 molten metal in the crucible; and means re- sponsive to the thermometer tube for varying the input of the auxiliary heater.
- 50 20. In combination, a crucible adapted to contain a relatively large mass of molten metal, an electric heater in the crucible, an outlet adapted to receive molten metal periodically from the crucible, an auxiliary electric heater for maintaining the molten metal in the outlet at the temperature of the relatively large mass in the crucible, and a regulator comprising a thermometer tube immersed in the relatively large mass of molten metal in the crucible; and means re- 70 sponsive to the thermometer tube for automatically opening and closing the circuit of the crucible heater and for varying the input of the auxiliary heater.
- 55 21. A heat regulating system for type setting machine crucibles comprising an immersion heater having a relatively low resistance section, an outlet heater and automatic means dependent upon pre-determined variations of the temperature of the metal within the crucible for opening and closing the circuit of the immersion heater 80 except the low resistance section and means for varying the heat generated in the outlet heater.
- 60 22. A heat regulating system for type setting machine crucibles comprising immersion heaters having a relatively low resistance section manually controlled means for short circuiting the low resistance section and automatic means dependent upon the temperature of the metal in the body of the crucible for interrupting the short circuit to include the low resistance section of the immersion heaters and for disconnecting the remainder of the immersion heaters 90 from the circuit.
- 65 23. A heat regulating system for type setting machine crucibles comprising a heater for the metal in the body of the crucible, an outlet heater and means for connecting a section of the body heater in the pre-determined relation to the outlet heater to relatively reduce the heat generated in the outlet heater.
- 70 24. A heat regulating system for a liquid containing receptacle having a branch, comprising a heater for the liquid in the body of the receptacle, a branch heater and means for connecting a section of the body heater in the predetermined relation to the branch heater to relatively reduce the heat generated in the branch heater.
- 75 25. A heat regulating system for type setting machine crucibles, comprising a heater for the body of the well, a heater for the outlet, regulating means dependent upon the temperature of the metal in the body of the well, and a switch adapted to modify the circuit relations between the two heaters, whereby either both heaters are completely excluded from the circuit by said regulating 125 130

means or one of said heaters is substantially cut out and the heat generated in the other reduced.

26. A heat regulating system for type-setting machine crucibles, comprising a heater for the body of the well, a heater for the outlet, regulating means dependent upon the temperature of the metal in the body of the well, and a switch adapted to modify the circuit relations between the two heaters, whereby either both heaters are completely excluded from the circuit by said regulating means or a section of one of said heaters is connected in series relation to the other and the remainder of the one disconnected from the circuit.

27. A heat regulating system for type-setting machine crucibles, comprising a

heater for the body of the well, a heater for the outlet, regulating means dependent upon 20 the temperature of the metal in the body of the well, a switch adapted to modify the circuit relations between the two heaters, whereby either both of said heaters are excluded from the circuit by said regulating 25 means or a portion of the heater for the body of the well is connected in series relation to the outlet heater.

In witness whereof, I have hereunto set my hand in the presence of two subscribing 30 witnesses, this 15th day of April, 1914.
